UNITED STATES PATENT OFFICE

157,707

SHOE DAUBER

Andrew P. Shelsey, Flushing, N. Y.

Application June 11, 1949, Serial No. 3,206

Term of patent 7 years

(Cl. D9—2)

To all whom it may concern:

Be it known that I, Andrew P. Shelsey, a citizen of the United States, residing in Flushing, in the county of Queens and State of New York, have invented a new, original, and ornamental Design for a Shoe Dauber, of which the following is a specification, reference being had to the accompanying drawing, forming part thereof.

Fig. 1 is a perspective view of a shoe dauber, showing my new design with both caps in closed position.

Fig. 2 is a top plan view of Fig. 1.

Fig. 3 is a sectional view taken on the line 3—3 of Fig. 2.

Fig. 4 is a side elevational view of Fig. 1.

Fig. 5 is a side elevational view of my design

showing each of the cap portions in open position.

I claim:

The ornamental design for a shoe dauber, substantially as shown.

ANDREW P. SHELSEY.
